UNITED STATES PATENT OFFICE

WALDEMAR D. KMENTT, OF AKRON, OHIO, ASSIGNOR TO THE B. F. GOODRICH COMPANY,
OF NEW YORK, N. Y., A CORPORATION OF NEW YORK

APPARATUS FOR CLASSIFYING WASHERS OR THE LIKE

Application filed February 23, 1929. Serial No. 341,982.

This invention relates to apparatus for classifying articles such as the frusto-conical washers which are incorporated in rubber heels for example, according to a determinate standard of maximum size or dimension. Washers may exceed the maximum limit when the metal composing them is too thick, when burrs project from their surfaces, or when they are bent or otherwise deformed.

10 The apparatus is especially useful for selecting washers to be used in apparatus for mounting washers upon the supporting pins of rubber-heel molds, wherein the washers require to be substantially perfect in form so as to pass in orderly procession down feed-chutes to the mold pins, such an apparatus being shown in my copending application for Letters Patent filed March 5, 1929, Serial No. 344,281.

20 The chief objects of my invention are to provide an improved apparatus for automatically and rapidly separating perfect washers from a mass of washers including imperfect ones. Other objects will be manifest 25 as the specification proceeds.

Of the accompanying drawings:

Fig. 1 is a transverse section through apparatus embodying and adapted to carry out my invention in its preferred form.

30 Fig. 2 is a section on line 2—2 of Fig. 1.

Fig. 3 is a side elevation of the apparatus as viewed from the right of Fig. 1.

Fig. 4 is a section on line 4—4 of Fig. 3.

Referring to the drawings, the apparatus 35 comprises a pair of spaced-apart, upright brackets 10, 10, the upper portions of which are formed respectively with journals 11, 11 for a rotatable shaft 12 mounted therein at its respective end portions, one end portion 40 of the shaft extending beyond its journal and being there provided with a sprocket 13 which is engaged by a sprocket chain 14 connected with a suitable source of power (not shown).

45 Mounted upon the shaft 12 is a hollow drum or hopper 15 comprising a generally cylindrical shell 16 and having end-walls 17, 17. A partition 18 is mounted within the hopper 15, being diametrically disposed 50 therein so as to divide the hopper into two

longitudinal chambers. The shell 16 is provided with oppositely disposed openings through which respective charges 19, 19 of washers to be classified are introduced into the chambers, said openings being provided 55 with respective closures or covers 20, 20 hinged to the shell at 20^a, 20^a. The shell 16 also is provided with relatively narrow longitudinal openings or slots 21, 21, extending from one end wall 17 to the other, said slots 60 being oppositely disposed in the shell and positioned adjacent the opposite margins of the partition 18 at opposite sides thereof. The slots 21 are adapted to permit washers classified as acceptable by classifying mechanism 65 within the respective chambers to escape from said chambers.

Extending lengthwise of each chamber adjacent the slot 21, and journaled in the end-walls 17, 17 of the hopper, is a rock-shaft 22 70 having mounted thereon a gate 23. The hub portion of the latter fills the space between the shell 16 and the rock-shaft 22 and the gate is formed with a tapered nose portion 24 at its free margin, one face of which is adapted 75 to bear against the partition 18 to close off the slot 21 from the interior of the chamber against the general escape of the charge of washers.

That face of the gate 23 which is adapted 80 to bear against the partition 18 is formed with a plurality of adjacent parallel grooves 25, 25, disposed transversely with relation to the rock-shaft 22, and the face of the partition 18 against which said gate is adapted 85 to bear is formed with a plurality of parallel ribs 26, 26 which ribs are disposed parallel to and intermediate the grooves 25 of the gate 23. The ribs 26 define intermediate grooves 27, 27 in the partition 18, which grooves are associated with the respective grooves 25 of the gate 23, when the latter bears against the partition 18, to define a plurality of chutes or passages. As clearly 90 shown in Fig. 2, the grooves 25 have sloped sides so that the chutes accommodate the frusto-conical washers commonly used in rubber heels.

The arrangement of the chutes is such that 95 washers may pass therethrough, from the in- 100

terior of the chamber to the discharge slot 21 therein, and the passages are of such size and shape that only such washers as conform closely to the acceptable standard of size and dimension will pass freely therethrough, other washers jamming in the chutes or the entrances thereof or not entering at all. The ribs 26 extend from beneath the gate 23 substantially to the middle of the partition 18 so that washers moving across the partition toward the gate 23 will align themselves with the grooves therein before reaching the gate.

Each of the rock-shafts 22 has one of its end portions extended through one end-wall 17 of the hopper 15 and provided outside thereof with a lever-arm 28 having a roller 29 journaled at its free end, said rollers being yieldingly urged against a stationary cam 30 having its cam surface surrounding the axis of the hopper, the cam being secured to the journal bracket 10 by a screw 31. The cam 30 comprises two concentric zones of which one zone, 30^a, is relatively short and has a greater radius than the other zone of the cam. Tension springs 32, 32 each secured at one of its ends to one of the lever arms 28 and at its other end to a stud 33 projecting laterally from the end-wall 17 are provided for urging the cam-rollers 29 against the cam 30.

The arrangement is such that the cam 30 is adapted to swing the gates 23 away from the partition 18, and thus to open the chutes provided by the grooves 25, 27 in the gates and partition, as each gate reaches a determinate high position in the orbit of the hopper.

Mounted in each chamber of the hopper 15 is a baffle 34 comprising a sheet-metal structure having an arcuate portion concentric with the hopper and a radially disposed end portion. Each baffle extends longitudinally of the chamber throughout its length and the end portions of each baffle adjacent one edge thereof are provided with respective integral ears, such as the ears 35, 35, Fig. 1, which are secured to the end walls 17 of the hopper, and the opposite marginal portions of the baffles are secured to respective tie-bolts 36, 36 which connect the end-walls 17 of the hopper to reinforce the same. The baffles 34 are disposed with their convex sides toward the gates 23, with the sides secured to the tie-bolts 36 positioned adjacent but spaced from the shell 16, and with their opposite sides adjacent but spaced from the partition 18.

The arrangement is such that only a limited number of washers 19 will pass between the baffles 34 and the partition 18, and provides that all washers that do so pass will continue to move past the nose of the gate 23 so that those washers which are properly positioned within the grooves between the

ribs 26 of the partition 18 will move into the chutes provided by said grooves and the grooves 25 of the gates.

A chute 37 is mounted below the hopper 15, between the brackets 10, for directing the washers 19 passing from the hopper into a suitable receptacle (not shown).

In the operation of the apparatus described, charges of the washers 19 to be sorted are introduced into the respective chambers of the hopper 15 through the openings provided therefor, the covers 20 of said openings are then locked in place, and rotation of the hopper is started. Since the mechanism in both chambers of the hopper is identical, it will be sufficient to describe only the operation of that in the right-hand chamber of the apparatus as it is viewed in Fig. 1, starting at the time the partition 18 is disposed in vertical position, with the gate 23 bearing against the partition, and the washers 19 resting in a heap in the bottom of the hopper.

The hopper rotates in a counter clockwise direction as viewed in Fig. 1 so that the mass of washers 19 rests substantially entirely upon the partition 18, at the opposite side thereof from the gate 23, when the partition attains horizontal position. As the partition moves past horizontal position and elevates that side of its structure upon which the washers 19 rest, the washers roll, slide, and fall transversely of the partition toward the gate 23 at the opposite side thereof, as shown in the left-hand chamber in Fig. 1. The proximity of the baffle 34 to the partition 18 permits only a relatively shallow stream of washers to pass therebetween, the washers intercepted by the baffle passing into the pocket formed by its concave side. The arrangement assures the passage of a greater number of washers past the tapered nose of the gate 23, than would occur if the entire mass of washers moved onto the gate and formed a heap thereupon which extended above the nose of the gate and thereby prevented the washers above the gate from moving toward it. Those washers which are within the limits of the size and shape desired and which fall into the grooves 25 between the ribs 26 of the partition 18 in proper position, move downward in said grooves and through the chutes provided by the latter and the grooves 25 in the adjacent face of the gate 23, and pass from the hopper 15 through the slot 21 in the shell 16. Washers which lie in the grooves of the partition in inverted position pass over the sloping nose of the gate 23 when they encounter the same, and said sloping nose permits other washers to slide over the gate so that they do not pile up and obstruct the entrances to the chutes.

As the partition 18 reaches and passes the vertical position, the mass of washers lying

against the gate 23 naturally seek the lowest point of the hopper and roll and slide away from the gate as the shell 16 moves under them and travels upward in its orbit. As the 5 partition 18 again passes horizontal position, the baffle 34 reaches a tilted position which permits the washers carried upon its concave face to flow therefrom and fall onto the mass of washers in the bottom of the hopper.

10 Before the gate 23 reaches the top of its orbit, wherein it is disposed in inverted position, the roller 29 on its lever-arm 28 engages the zone 30^a of the cam 30 with the result that the rock-shaft 22 is moved angularly in a 15 manner to swing the gate away from the partition 18, and thus to separate the grooved surfaces which define the chutes. Any defective washers which may have become jammed or lodged in the chutes are thus permitted to drop therefrom, into the mass of 20 washers at the bottom of the hopper, before said mass again is presented to the gate. The gate is closed by the spring 32 acting upon the lever-arm 28 when the roller 29 passes off 25 the zone 30^a of the cam 30.

This completes one cycle of operations for one chamber of the hopper 15, it being understood that the same operations occur in both chambers, successively as the hopper rotates.

30 When washers are no longer delivered from the discharge slots 21 of the hopper, the latter may be opened and the washers remaining in the hopper discarded as defective.

My invention is susceptible of modification, 35 and I do not wholly limit my claims to the exact procedure or specific construction shown and described.

I claim:

1. In apparatus for classifying articles, 40 the combination of a gravity chute adapted to permit the passage therethrough only of articles of acceptable dimensions, means for causing a supply of articles to fall in chance arrangement toward said chute, means in the 45 path of fall of the articles for diverting all but a shallow stream of the articles away from said chute, and means for retaining and subsequently returning the diverted articles to the common supply of articles.

50 2. In apparatus for classifying articles, the combination of a gravity chute, means for periodically feeding a supply of articles in chance arrangement toward said chute, a concave baffle so positioned with relation to 55 the course of the articles being fed as to divert and retain all but a shallow stream of said articles and means for inverting the baffle to restore the diverted articles to the rest of the supply articles.

60 3. In apparatus for classifying articles, the combination of a gravity classifying chute for the articles, means for feeding a mass of articles in chance arrangement toward said chute, an arcuate baffle so positioned with relation to the course of the 65

articles as to divert and retain some of the same, means for moving the chute and baffle to a position where the articles fall by gravity into a common mass remote from said chute, and means for opening said chute while it 70 is so positioned to clear the same of articles lodged therein.

4. In apparatus for classifying articles, the combination of an article-supporting member adapted to support a mass of the 75 articles, a gate at one side of said member formed with a groove and co-operating with said member to define a chute, means for tilting said article-supporting member to different positions to cause the articles to feed by 80 gravity respectively toward and away from said chute, and means for opening said gate to clear it of articles lodged therein.

5. In apparatus for classifying articles, the combination of a hopper having a delivery aperture, a gate across said aperture formed with a groove adapted to permit the passage of articles of acceptable dimensions, means for periodically presenting a mass of 85 articles in chance arrangement to said gate, and means for periodically opening said gate to release articles lodged in the groove therein, at intervals alternating with the presenting of the mass of articles to the gate. 90

6. Apparatus as defined in claim 5 including means for rotating the hopper to effect 95 the periodic presentation of the mass of articles to the gate.

7. In apparatus for classifying articles, 100 the combination of a rotatable hopper having delivery openings at opposite sides thereof, a partition in said hopper dividing it into two chambers with the delivery openings adjacent said partition, respective gates associated with said partition for closing said delivery openings, said gates being formed with respective grooves for admitting the passage therethrough of articles of acceptable dimensions, means for rotating the hopper to present masses of articles in the respective chambers periodically to the gates therein, and means for opening the gates as they attain 105 a determinate position in their orbit. 110

In witness whereof I have hereunto set my hand this 20th day of February, 1929. 115
